ART OF PAPER BAGS AND METHOD OF PRODUCING THE SAME

Filed Sept. 12, 1929

UNITED STATES PATENT OFFICE

JOSEPH D. CRAMER AND ALBERT J. ROGERS, OF GOSHEN, INDIANA, ASSIGNEES TO THE CHASE BAG COMPANY, OF NEW YORK, N. Y., A CORPORATION OF DELAWARE

ART OF PAPER BAGS AND METHOD OF PRODUCING THE SAME

Application filed September 12, 1929. Serial No. 392,109.

This invention relates to paper bags, and a method of producing the same, and the primary object of the invention is to provide a strong and durable open mesh bag made of 5 colored strands of paper treated and woven in the mode and manner hereinafter described, whereby perishable goods, such as fruits, vegetables, etc., may be openly stored and preserved, and safely handled and transported in bulk. The construction of the bag, and the steps taken to produce the same, provide an open-work receptacle or container having walls of substantial durability and strength, notwithstanding that the material 10 is paper and coarsely woven to provide open meshes of relatively large area. Wide open meshes are employed to display the goods plainly and visibly in their natural state and colors and to freely ventilate and expose the 15 goods to light and air. The strands in the open mesh fabric are also colored to heighten or modify the natural color of the goods when viewed through the open meshes. For example, oranges, or fruits, not fully ripened, 20 are displayed more invitingly and attractively, when packed for handling and shipment in an open work bag made of red and tan colored strands of paper. The colored strands are fast weathering colors to avoid 25 spotting or tainting of the goods, especially edible goods brought into contact during shipment with the meshes of the bag. The paper strands are also treated to repel moisture and water and to withstand exposure to 30 all kinds of weather without deteriorating or weakening appreciably, having in mind in that connection that these open-work bags are also relatively large and called upon when both wet and dry to carry heavy loads. 35 The treatment of the paper strands and the particular steps involved in weaving the fabric have the following object in view also,—that of producing a flat stiffy-pliable open mesh fabric, in which, the warp and weft 40 strands of paper will be firmly interlocked in widely-spaced union and capable of resisting displacement or disarrangement when the bag is being made, used and handled. The warp strands are also stiffer or less pliable 45 than the weft strands in the final product or bag although made conversely so in weaving them together. As a result the finished bag is flat when unfilled and will retain that shape under repeated handling, and the woven walls are tough and strong and possess 55 resilient or spring properties, notwithstanding that the bag is merely an open net-work composed entirely of paper.

As an exemplification of a bag made and constructed according to our invention, reference may be had to the accompanying drawing, in which Fig. 1 represents a side view of a completed bag; Fig. 2 a sectional view longitudinally thereof; Fig. 3 a sectional view transversely of the bag; Fig. 4 a larger 60 detail view of a small portion of the woven fabric; and Fig. 5 an enlarged side elevation of a twisted paper strand such as used in producing the bag fabric.

The first steps taken involve the making 65 of threads or strands of substantial tensile strength from thin flat strips 2 of paper approximately one-eighth to one-fourth of an inch in width. Preferably the paper stock contains only a limited amount of sizing, as 70 an excess of sizing is detrimental to the final product. The strip has the same natural color, as the stock, before spinning it into a strand, and to obtain durable and quite brilliant colors, and also uniform coloring 75 results, the paper strip is treated and impregnated with a colored solution co-incidently with the spinning operations.

Thus the strip is unwound from a reel, and 80 as it is being twisted or spun into a round thread or strand it is colored or dyed, using any suitable spinning machine for the purpose. The spinning of the strip to uniform diameter or thickness, without breakage, is 85 promoted by impregnating or saturating the strip of paper with a colored solution while it is passing rapidly from the reel to a bobbin or spool carried by a rapidly revolving spindle.

A preferred spinning solution consists of 90 an aqueous composition containing soap emulsified with a preservative oil composed of natural glycerides, in any suitable proportions, including a phenol concentrated dye 95 of any desired color.

The strip is dyed or colored uniformly throughout by the application of the spinning solution itself, preliminary to twisting or spinning of the strip into a round thread or strand. In addition to coloring the strip 5 the solution imparts water repellent properties to the strand and promotes the spinning of the strip into a strand of uniform size and tensile strength.

10 The twisted strand is in a moist or wet state when wound under tension on the spool or bobbin of the spinning machine. Consequently, the strand remains under tension and will not unravel or untwist when it is permitted to dry on the spool or bobbin. However, it may be wound under tension upon a 15 reel, without unraveling, to permit immediate use thereof in its wet or damp state.

The next steps taken involve the weaving 20 of the dry and moist strands together before the latter have dried and set. Weaving proceeds on any suitable weaving machine, using the moist strands for the warp, and the dry strands for the weft. In producing a variety 25 colored mesh of natural and colored strands, such as tan and red strands, the colored dry strands *a* are used for the weft, and the wet strands *b* of natural color are used for the warp. Accordingly, the respective strands 30 are not weakened or easily broken in weaving operations, and later other advantages accrue.

Thus the moist warp strands of twisted paper are stretched and under tension during 35 weaving operations, and the colored dry strands of twisted paper are passed back and forth by the shuttle between the warp strands to produce the weft or woof. In interlacing or weaving the strands together 40 the wet warp will buckle or bend sharply and readily and the dry woof or weft strand will embed itself in the wet strand. In that way a wide open mesh may be made and the crossed strands interlocked in uniformly 45 spaced relation. Then this openly woven fabric composed of interlaced dry and wet strands, is wound fairly tightly in a roll, the warp strand being wound spirally in the roll. When so rolled the wet warp strands of 50 twisted paper are permitted to dry, and in drying they contract and become stiffer than the colored weft or woof strands. Thus the tension of the warp strands is enhanced and have greater inherent tension than the weft 55 strands, and all the strands become more tightly interlocked than when first woven. Consequently, when the mesh fabric is unrolled and handled in a dry flat state preparatory to and also subsequent to the making 60 of a bag therefrom, the interlaced strands withstand handling and use without material relative displacement of the strands, or change in the size of the inter-spaces or open places. This open mesh 65 fabric is stiffly flexible and will lie flat so

that it may be readily folded and sewn into bag form without mal-formation.

In making the bag, a piece of the open work fabric is severed transversely thereof from selvedge 3 to selvedge 3', and the length of the severed piece corresponds approximately to the width of the bag. Then the severed piece is folded at its middle parallel with the selvedges, and the severed edges are folded and sewn together, lengthwise of the folded piece parallel with the weft strands *a* and across the warp strands *b*. Preferably the cut edges are turned inwardly to form flaps or folds *c* which may be placed face to face and sewed together to provide a four-ply seam 4 at opposite sides of the folded material. The selvedges border the open mouth of the bag, and the warp strands extend transversely of the bag. Thus in a tan and red colored bag, the red colored weft strands *a* extend lengthwise of the bag, and the warp strands *b* of tan extend across the bag.

The red or colored weft strands *a* in the finished bag B are more pliable than the warp strands *b*, and the warp strands are stiffer and possess greater spring or recoil properties than the colored weft strands. However, both strands are water repellent and possess such inherent toughness and tensile strength that a bag made and constructed as described herein will bear heavy loads without bursting, notwithstanding that the bag walls are composed of twisted strands of paper separated a substantial distance apart to provide relatively large openings or interspaces for the useful purposes hereinbefore explained.

What we claim, is:

1. A paper bag, composed of tightly twisted flat strands of paper interwoven in openly spaced relation and possessing water repellent properties, the warp strands being more stiffly resilient and having greater inherent tension than the weft strands, and said warp strands being permanently contracted with the weft strands embedded therein to effect a locking union at the intersecting places in the strands.

2. A paper bag fabric, composed of tightly twisted strands of paper interwoven in spaced relation and possessing water repellent properties, and the weft strands being colored and embedded sharply in the warp strands, and the warp strands being more stiffly resilient and having greater inherent tension than the weft strands.

3. A paper bag fabric, composed of tightly-twisted strands of paper of contrasting colors interwoven in spaced relation and possessing water repellent properties, the weft strands being more pliable than the warp strands and sharply embedded in the stiffer strands.

4. A paper bag fabric, composed of tightly-twisted strands of sized paper tightly inter-

woven together in widely spaced relation, and including strands impregnated with a preservative oil, the weft strands being more pliable than the warp strands and embedded 5 therein with interlocking effect at the intersections.

5. A paper bag, formed of a piece of open mesh fabric composed of tightly-twisted strands of paper treated with a preservative 10 and interwoven together in interlocking union, the respective warp and weft strands differing in stiffness and the softer strands being embedded locally in the harder strands at the intersections.

15 6. A paper bag fabric, composed of a single flat piece of open mesh made of colored strands of tightly-twisted paper interwoven tightly together with other tightly-twisted strands of paper treated with a preservative 20 oil, said open mesh fabric having selvedges and folded at its middle between and parallel with its selvedges and the selvedges brought together to form the mouth of the bag.

7. A method of making a paper bag fabric, 25 consisting in weaving wet and dry strands of tightly-twisted paper into a flat open mesh body, drying the wet strands of the woven fabric under longitudinal tension, and then severing the same transversely from selvedge 30 to selvedge to permit the severed piece to be folded midway upon itself parallel with the selvedges.

8. A method of making a paper bag fabric, 35 consisting in weaving wet strands of tightly-twisted strips of paper treated with a preservative substance together with dry strands of tightly-twisted strips of paper treated with a preservative coloring substance, winding the woven material in a roll, and drying the 40 wet strands while these wet strands are under tension and tightly engaged with the dry strands.

9. A method of making bags, consisting in weaving wet warp strands of tightly-twisted 45 strips of paper in open net-work relation with dried weft strands of tightly-twisted strips of colored paper, drying the wet strands under tension subsequent to said weaving steps, and forming a flat bag from the completely 50 dried material.

In testimony whereof we affix our signatures.

JOSEPH D. CRAMER.
